UNITED STATES PATENT OFFICE.

EVALD J. ENGMAN, OF SYRACUSE, NEW YORK, ASSIGNOR TO THE WILL & BAUMER COMPANY, OF SYRACUSE, NEW YORK, A CORPORATION OF NEW YORK.

CANDLE-MAKING MACHINE.

1,168,938.

Specification of Letters Patent. Patented Jan. 18, 1916.

Application filed July 22, 1914. Serial No. 852,397.

To all whom it may concern:

Be it known that I, EVALD J. ENGMAN, a citizen of the United States, and resident of Syracuse, in the county of Onondaga, in the State of New York, have invented new and useful Improvements in Candle-Making Machines, of which the following, taken in connection with the accompanying drawings, is a full, clear, and exact description.

10 This invention relates to certain improvements in candle making machines, as applied more particularly to the molding or finishing of the bases or holder-ends of such candles.

15 The main object is to provide a more expeditious and economical method of finishing the ends of the candles to the desired form and size than has heretofore been practised, whereby the output for a given 20 period of time may be greatly increased with a corresponding reduction in the amount of labor employed and at the same time establishing greater uniformity in the form and size and smoothness of finish of 25 such candle ends.

Another object is to provide simple mechanism operating in synchronism with the forming means for softening the ends of the candles just prior to their being fed 30 into the finishing molds.

Other objects and uses relating to specific parts of the machine will be brought out in the following description.

In the drawings—Figure 1 is a side elevation of a candle finishing machine embodying the various features of my invention. Fig. 2 is a top plan of the same machine. Fig. 3 is a longitudinal vertical sectional view taken on line 3—3, Fig. 2. Fig. 4 is a horizontal sectional view in the plane of the main driving shaft taken on line 4—4, Fig. 3. Fig. 5 is a transverse vertical sectional view taken on line 5—5, Fig. 2. Fig. 6 is a detail sectional view of a portion of the carrier feed taken on line 6—6, Fig. 2. Figs. 7 and 8 are transverse vertical sectional views taken respectively in the plane of line 7—7, Fig. 3, and on line 8—8, Fig. 9. Fig. 9 is an enlarged longitudinal vertical section of the candle finishing dies and also the jaws for gripping the candles and feeding them end foremost into the finishing dies, the adjacent portion of the jaw operating mechanism and stamping die 55 being shown in elevation. Fig. 10 is a ver-

tical section of the vat for the candle softening fluid and means for conveying the candles therethrough. Fig. 11 is a top plan, partly in section, of the actuating device for the rotary candle conveyer. Fig. 12 is a side view of the device for raising and lowering the upper side of the endless candle conveyer to bring the candles into registration with the finishing dies.

Candle softening device.—The candles 65 —a— which are previously molded by any well known method to approximately the desired size and form are placed by hand in an upright position in a rotary carrier —1— having the lower portion thereof movable 70 within a heater vat or tank —2— containing a body of hot water or other suitable heating fluid for softening the bases or lower ends of the candles preparatory to molding or finishing such ends by associated mechanism hereinafter described.

The carrier —1— comprises a vertical shaft —3— journaled in a central bearing —4— in the vat —2— and having secured thereto a sleeve —5— carrying circular 80 plates —6— and —7— which are held in spaced relation one above the other by diametrically opposite stays —8— and —9—, the shaft —3— being also provided with a circular plate —10— adjustable vertically 85 thereon above the plate —7— and held in its adjusted position by a set screw —11—.

The bottom plate —6— is imperforate and disposed below the water level to form a rest for the lower ends of the candles, 90 while the plates —7— and —10— are preferably disposed above the water level and are provided with concentric rows of apertures —12— arranged in vertical alinement to hold the candles in upright positions 95 thereby causing the lower ends of such candles to be moved through the heating fluid to soften the same, the object of the vertical adjustment of the upper plate —7— being to adapt the carrier for candles of 100 different lengths.

The heating fluid, as water, may be supplied to the vat —2— through a supply pipe —13— and is maintained at a predetermined level by an overflow pipe —14—, it being 105 heated preferably by steam admitted through a pipe —15—, the upper end of the overflow having an adjustable section —14'— to vary the liquid level as desired.

The rotation of the carrier is intermittent 110

and synchronized with the movement of the candle finishing mechanism by means of a ratchet wheel —16— on the lower end of the shaft —3— and a pawl —17— which is mounted on a rock arm —18—, the latter being loosely mounted on the lower end of said shaft and connected to an eccentric —19— on a main driving shaft —20— through the medium of pitmans —21— and —21'— and crank arm —22—, as shown in Figs. 1 and 2.

Candle finishing mechanism.—The softened candles are removed by hand from the carrier —1— and placed in a horizontal position upon a table —23— with their bases abutting against a guide rib —24— and are then fed by hand upon an endless conveyer —25— consisting of a series of parallel link belts —25'— mounted in spaced relation upon sprocket drums —26— and provided with concave candle supporting seats —27— which are alined transversely of the belts and serve to register the candles in pairs between suitable jaws —28— and into registration with coöperative finishing or molding dies —29— and —30— where the desired form and finish is imparted to the bases of the candles after which the finished candles are discharged by the same conveyer belts to a delivery table —31— (the receiving and delivery tables being shown by dotted lines).

The sprockets —26— are secured to suitable shafts —32— and —32'— which are journaled upon a main supporting frame —33— at the front and rear of the finishing dies —29— and —30— and are operated intermittently from the main driving shaft —20— by means of a cam —34—, and a rock-arm —35— which is connected by a link —36— to a crank arm —37— carrying a pawl —38— for engaging a ratchet wheel —39— on the shaft —32— and thereby rotating said wheel one tooth space at a time, the rock-arm being provided with a roller —40— held against the face of the cam by a retracting spring —41—, Fig. 4.

The main shaft —20— is provided with a tight pulley —42— adapted to be belted to any available source of power for transmitting the desired speed of rotation to said shaft, while the mechanism just previously described for imparting intermittent movement to the conveyer —25— is so constructed and timed as to cause the candle holders —27— to be successively passed in pairs to a certain point, in this instance in registration with the gripping and feeding jaws —28—, preparatory to forcing the registering candles endwise into their respective dies or molds —29— and —30—.

The upper sides of the link belts —25'— travel in a substantially horizontal plane a slight distance below that of the meeting faces of the jaws —28— when the latter are closed upon the candles, or rather in such a plane as to cause the candles resting upon

their respective seats —27— to be substantially coaxial with the dies —30—, and in order to accomplish this in a simple manner and with a practical degree of accuracy, the intermediate portions of the upper sides of the chains are caused to ride in vertically adjustable guides —43— having pendant stems —44— guided in upright bearings —45— and normally resting on crank-arms —46— which are secured to a rock-shaft —47— having an operating handle —48— and a perforated segment —49—, the latter being provided with an eccentric row of perforations —50— for receiving a locking pin —51— by which the guides —43— resting upon the crank-arms —46— may be held in any of their adjusted positions.

The locking pin —51— is adapted to enter any one of a series of apertures which may be formed in a radial line in the adjacent portion of the frame —33—, each aperture being in a different concentric circle corresponding to those concentric circles in which the eccentric row of apertures —50— are located, thereby establishing a close adjustment for the guides —43— and at the same time preventing the insertion of the locking pin —51— into any other aperture in the frame —33— except the aperture —50— corresponding therewith.

The conveyer —25— is operated only when the jaws —28— and —29— are in their normal open positions, but as soon as it has completed one of its movements in the act of registering a pair of candles with the jaws —28— and —29— and also with the dies —30—, the jaws —28— which are locked in a vertical plane between the two link belts nearest to the dies —30—, are brought together upon the interposed portions of the candles to grip the same with sufficient firmness to move them endwise between the jaw dies —29— and into the socket dies —30—, and for this purpose the jaws —28— are mounted in suitable heads —52— having stems or plunger rods —53— guided in vertical bearings —54— and operably connected to the adjacent ends of suitable levers —55— and —56—. These levers are fulcrumed intermediate their ends at —57— and —57'— upon a reciprocatory frame —58— which is movable at right angles to the direction of movement of the conveyer —25— and therefore parallel with the axes of the candles and socket dies —30—, so that when the candles are gripped by the jaws —28— their previously softened ends may be forced into the socket dies —30— to impart the desired conformation thereto, preparatory to being additionally molded by the jaw dies —29— in a manner presently described. The jaw supporting heads —52— are therefore reciprocated toward and from each other by means of the levers —55— and —56— and are held against turning by

guide pins —59— which are slidable in apertures —60— in the frame —58—, as shown more clearly in Fig. 3.

The lever —55— is connected directly to a collar —61— which is adjustably mounted on the lower jaw stem —53— and is held in its adjusted position by a set screw —62—, the upper lever —56— being connected to a collar —63— which has a limited sliding movement on the upper stem —53— between two collars —64—, which are also adjustably mounted on the stem —53— and are held in their adjusted position by set screws —65—, a spring —66— being interposed between the collar —63— and the underlying collar —65— to permit the jaws —28— to be brought together upon the candle under yielding pressure, so as to avoid mutilation of the candle.

In order that the same jaws —28— may be used for gripping candles of different diameters, they are rotatably mounted in their respective heads —52— and are each provided with a plurality of, in this instance four, concave seats —67— of different radii and are adjusted so that the concave seats of the same radii of opposed jaws face each other, said jaws being held in their adjusted position by removable locking pins —68—, as shown in Fig. 3.

When the candles are brought into registration with the jaws —28— by the movement of the conveyer —25—, said jaws are closed upon the candle to grip the same preparatory to feeding them endwise into the socket dies —30—, and for this purpose the outer ends of the levers —55— and —56— are provided with open-ended slots —69— and —70— and cam faces —71— and —72— for engaging rollers —73— on the opposite ends of an upright lever —74— which is fulcrumed intermediate its ends at —75— upon the head of the U-shaped frame —58—, as shown more clearly in Figs. 3 and 9, said cams being reversely arranged and of such inclination as to move the jaws —28— equal distances toward each other as the lever —74— is rocked in one direction, the portions of the outer ends of the levers at the inner sides of the slots —69— and —70— constituting cams —76— and —77— so constructed as to operate the levers —55— and —56— to restore the jaws —28— to their normal open positions when the lever —74— is moved in the opposite direction.

The means for actuating the lever —74— consist of an upright lever —78— fulcrumed at —79— upon the main supporting frame —33— below the main driving shaft —20— and provided intermediate its ends with a roller bearing —80— adapted to be engaged by opposite cams —81— and —82— on a sleeve —83— which is secured to the main shaft —20—, the upper end of the lever —78— being engaged with a roller —84—

on the lower end of the lever —74— and coaxial with the roller —73—, so that when the lever —78— is operated in one direction by the cam —81— it will impart motion to the lever —74— and cause the rollers —73— to ride up their respective cams —71— and —72— to operate the corresponding levers —55— and —56— for closing the jaws —28— upon the candle, in which position the jaws will remain until the cam —82— operates the lever —78— in the opposite direction to restore the jaws to their normal open positions, such operations taking place once during each revolution of the main driving shaft.

The reciprocating frame —58— is held in its upright position against turning by guide pins —85— projecting from the adjacent portion of the main supporting frame —33— into guide openings —86— in said head, which latter is provided with a horizontal projecting stem or rod —87— movable axially in a bearing —88— on the main supporting frame, as shown in Figs. 2 and 3.

The outer end of the stem —87— is provided with an adjustable collar —89— held in place by a set screw —90— and engaged by an upright lever —91— which is fulcrumed at —92— on the main supporting frame —33— below the main driving shaft —20— and has its intermediate portion provided with a roller bearing —93— riding in a grooved cam —94— on said main driving shaft, the cam —94— being so constructed as to reciprocate the frame —58— and jaws —28— carried thereby a sufficient distance to enter the bases of the candles held by said jaws into and out of the die sockets —30—, this operation following immediately after the jaws —28— have been forced to their gripping positions upon the candles, it being understood that the action of the lever —74— to open and close the jaws —28— is entirely independent of the reciprocating movement of the frame —58— which carries the lever —74— and jaws —28— bodily back and forth toward and from the die socket —30—. These die sockets —30— are, in this instance, conical or tapered outwardly and corrugated transversely to impart a corresponding corrugated finish to the softened ends of the candles, and are spaced apart side by side a distance corresponding to the spacings of the candle-holders or seats —27— of each pair, so that two of the candles may be operated upon at a time, and when their softened ends are forced into the conical sockets —30— they will be slightly enlarged at the bases of the cones by reason of the fact that a portion of the material displaced from the smaller ends of the cones will be forced back toward the main body of the candles, and this candle material which is

120
125
130

thus forced back is utilized to form a fillet or bead —*a'*— at the base of the cone, said bead or fillet being formed by the jaws —*29*.

5 At about the same time that the softened ends of the candles are forced into the die sockets —*30*— these jaws —*29*— are closed by means of a lever —*95*— which is fulcrumed intermediate its ends at —*96*— 10 upon the main supporting frame —*33*— and has its opposite ends provided with rollers —*97*— and —*98*— in coöperative engagement respectively with cam levers —*99*— and —*100*—. These cam levers are secured 15 to rock shafts —*101*— and —*102*— on the main supporting frame and their free ends are provided with cam faces —*103*— and —*104*— adapted to be engaged by their respective rollers —*97*— and —*98*— for closing the jaws when the lever —*95*— is rocked in one direction, said cam levers being provided with additional cams —*105*— and —*106*— adapted to be engaged by the corresponding rollers for opening said jaws 20 25 when the lever —*95*— is rocked in the opposite direction.

The rock shafts are provided with crank arms —*107*— and —*108*— pivotally connected to their respective jaws —*29*— for 30 imparting reciprocatory motion thereto in reverse directions, the jaw being guided in ways —*109*— on the main supporting frame —*33*— so as to travel in close proximity to the adjacent face of the die sockets —*30*— and are provided with semi-circular recesses —*110*— to form the beads on the adjacent portions of the candle or at the bases of the cones thereof.

35 The conical sockets —*30*— are preferably formed in separate sleeves —*111*— which are secured in openings —*112*— in the main frame —*33*— by means of screw caps —*113*— having central lengthwise apertures coaxial with their respective sockets —*30*— for receiving stamping plungers —*114*— for impressing upon the ends of the candles a trade-mark or other distinguishing character. These plungers —*114*— are 40 adapted to be operated against the action 45 of retracting springs —*115*— by means of a crank arm —*116*— mounted upon a rock shaft —*117*— and provided with oppositely projecting studs or pins —*118*— for moving the plungers inwardly simultaneously.

50 55 The rock shaft —*117*— is provided with a crank arm —*119*— to which is pivotally connected the upper end of a rod or link —*120*— having its lower end guided in a suitable bearing —*121*— on the main supporting frame —*33*— and engaged with a periphery of a face cam —*122*— on the main shaft —*20*—, as shown more clearly in Figs. 5 and 9.

55 The means for actuating the lever —*95*— for opening and closing the jaws —*29*— con-

sists of a lever —*123*— fulcrumed at —*124*— to the main supporting frame —*33*— below the main shaft —*20*— and having its intermediate portion provided with a roller —*125*— riding in a cam groove —*126*— of a cam disk —*127*— also on the main shaft —*20*—, it being understood that the cam —*122*— is timed to operate the printing or stamping dies or plungers —*114*— while the base of the candle is being molded in the 75 conical die —*30*— and while the jaws —*28*— and —*29*— are still closed upon the candle and the jaws —*28*— are shifted to their extreme position toward the die sockets —*30*—.

The caps —*113*— are provided with air 80 vents —*128*— leading from the smaller ends of their respective die sockets —*30*— to the atmosphere to relieve the candles and also the plungers —*114*— from excessive air pressure or suction when moving into and out of 85 said sockets.

The collar —*89'*— is slidably mounted on the outer end of the stem —*87*— of the reciprocatory frame —*58*— and engages a spring buffer —*129*— which is interposed between 90 the outer end of said collar and a stop nut —*130*— so as to permit the candles to be forced into the die sockets —*30*— by the gripping jaws —*28*— under a yielding pressure, which aids materially in causing the 95 dies —*29*— and —*30*— to impart the desired finish to the candles.

The operation briefly described is as follows: The partially formed candles are placed by hand in the apertures of the carrier —*1*— with their lower ends dipping in the heated fluid in the chamber —*2*— so that as the carrier is rotated a whole or a part of a revolution, the bases of the candles are gradually softened. The candles are 105 then removed from the carrier and placed upon the table —*23*—, where they are engaged by the conveyer —*25*— and fed in uniformly spaced relation between the open jaws —*28*— with their softened bases in 110 register with the finishing dies or molds —*29*— and —*30*—. The movement of the conveyer —*25*— then ceases temporarily 115 while the jaws —*28*— are closed upon the main bodies of the candles to firmly grip and hold the same, whereupon the closed jaws with the candles between them are moved endwise to enter the bases of the candles between the then open jaws —*29*— and into the sockets —*30*—. Immediately 120 following the entrance of the bases of the candles into the sockets —*30*— for imparting the desired configuration to said bases, the molding sections or jaws —*29*— are closed upon the adjacent portion of said 125 bases to impart additional ornamental configuration thereto, thus giving the bases of the candles the desired finish. While the candle is thus held, the plungers —*114*— are advanced against the end face of the candle 130

base to leave their imprint, which may be a trade-mark, thereon, thus completing the molding operation of the base of the candle. The plungers —114— are then withdrawn 5 and the jaws —29— opened, whereupon the jaws —28—, which still remain closed upon the candle, are returned to their starting positions and automatically opened to deposit the candles upon the same rests of the 10 conveyer —25— from which they were previously displaced, after which said conveyer is again advanced one step or two candle spaces to present another pair of candles to the gripping jaws —28— preparatory to a 15 repetition of the operation just described, each operation of finishing the candles taking place once during each revolution of the main driving shaft —20—.

What I claim is:

20 1. In a machine for molding the ends of candles, a die having a socket, means for gripping a candle and forcing it endwise into said socket and a conveyer for feeding the candles to the gripping means.

25 2. In a machine for molding the ends of candles, a socketed die and a candle gripping device movable one in relation to the other for forcing one end of a candle into the die, means for effecting such movement, 30 and additional means for conveying the candles to the gripping device.

35 3. In a machine for molding the ends of candles, a socketed die and a candle gripping device movable one in relation to the other for forcing one end of a candle into the die, means for effecting such movement, and means for feeding the candles sidewise into the gripping device.

40 4. In a machine for molding the ends of candles, a socketed die and a candle gripping device movable one in relation to the other for forcing one end of a candle into the die, means for effecting such movement, additional means for conveying the candles 45 to the gripping device and relatively movable die sections having semicircular meeting faces enlarged at their ends adjacent the die to receive the candle material forced up by the entrance of the candle into said die.

50 5. In a machine for molding the ends of candles, a die having a conical socket, opposed die sections movable radially across the open end of said socket and provided 55 with semicircular meeting faces enlarged at their ends adjacent the die, mechanism for gripping a candle and advancing it endwise between said die-sections and into the socket, mechanism for feeding the 60 candles to the gripping device and additional mechanism for operating the die sections all of said mechanisms being synchronized and deriving motion from the same source.

65 6. In a machine for molding the ends of

candles, a die having a socket, a candle gripping device movable toward and from the die and having transversely movable jaws, and mechanism for closing and opening said jaws a conveyer moving in synchronism with said mechanism for feeding the candles between the open jaws, and an additional mechanism for moving the closed jaws with the candle therein toward and from the die. 70

7. In a machine for molding the ends of candles, a socketed die, a candle gripping device, mechanism for shifting the gripping device toward and from the die to force the end of the candle into the socket, 80 and an endless conveyer for feeding candles to the gripping device. 75

8. In a machine for molding the ends of candles, a socketed die, a candle gripping device, means for shifting the gripping device toward and from the die to force the end of the candle into the socket, additional means for feeding candles to the gripping device, a candle heating apparatus having a rotary carrier for the candles, and means 85 synchronized with said feeding means for rotating the carrier. 90

9. In a machine for molding the ends of candles, the combination of a mold, means including a rotary candle carrier for subjecting the bases of the candles to a softening influence, means for rotating said carrier, and mechanism operating in synchronism with the carrier for conveying the softened candles into and out of the mold. 95 100

10. In a machine for molding the ends of candles, the combination of a plurality of parallel molds open at the same end, a gripping device for a corresponding number of candles movable toward and from the open 105 ends of the mold for forcing the candles endwise therein, and an endless conveyer for feeding the candles in equal numbers and in succession to the gripping devices.

11. In a machine for molding the ends of 110 candles, the combination of a device for softening the ends of the candles including a rotary carrier therefor, a mold for receiving the end of the candles, mechanism for gripping and feeding the candles endwise into the mold, and additional mechanism moving in synchronism with the rotary carrier for conveying the softened candles to the gripping and feeding device. 115

12. In a machine for molding the ends of 120 candles, the combination of a mold, gripping jaws for the candle, means for opening and closing the jaws, additional means for moving the jaws toward and from the mold, and an endless conveyer for feeding the candles 125 between the open jaws.

13. In a machine for molding the ends of candles, means for softening such ends including a rotary candle carrier, in combination with a mold for receiving the sof- 130

tened ends of the candles, a main driving shaft, a candle gripping and feeding device for moving the candles endwise into the mold, and means for transmitting motion from the main shaft to the gripping and feeding device.

14. In a machine for molding the ends of candles, means for softening such ends including a rotary candle carrier, in combination with a mold for receiving the softened ends of the candles, a main driving shaft, a candle gripping and feeding device for moving the candles endwise into the mold, means for transmitting motion from the main shaft to the gripping and feeding device, an endless conveyer for feeding the candles to the feeding and gripping device, and means for transmitting motion from the main driving shaft to said conveyer.

15. In a machine for molding the ends of candles, the combination of a socketed mold, gripping jaws movable toward and from each other transversely of the produced axis of the mold for gripping the periphery of the candles, said gripping jaws having an independent movement toward and from the mold for feeding the candles endwise thereinto, means for opening, and closing the jaws, and additional means for moving said jaws toward and from the mold.

16. In a machine for molding the ends of candles, the combination of a mold consist-

ing of a socketed member and a pair of mold sections movable across the open end of the socketed member, means for operating said mold sections, and means for gripping and feeding the candle endwise between said sections and into the socketed member comprising a pair of jaws movable transversely of the produced axis of the socketed member for gripping the periphery of the candle, said jaws having an independent movement toward and from the movable mold sections.

17. In a machine for molding the ends of candles, the combination of a mold consisting of a socketed member and a pair of mold sections movable across the open end of the socketed member, means for operating said mold sections, means for gripping and feeding the candle endwise between said sections and into the socketed member comprising a pair of jaws movable transversely of the produced axis of the socketed member for gripping the periphery of the candle, said jaws having an independent movement toward and from the movable mold sections, and an endless conveyer for feeding the candles to the gripping jaws.

In witness whereof I have hereunto set my hand this 20th day of July, 1914.

EVALD J. ENGMAN.
